UNITED STATES PATENT OFFICE.

WILLIAM H. MANNON, OF OURAY, COLORADO.

NON-REFILLABLE BOTTLE.

1,083,116.

Specification of Letters Patent. Patented Dec. 30, 1913.

Application filed June 1, 1912. Serial No. 700,986.

To all whom it may concern:

Be it known that I, WILLIAM H. MANNON, a citizen of the United States, residing at Ouray, in the county of Ouray and State of Colorado, have invented new and useful Improvements in Non-Refillable Bottles, of which the following is a specification.

This invention relates to bottles of the non-refillable type, the object of the invention being to provide a stopper for bottles, which stopper is of such construction that taken in connection with check valves arranged therein, it is impossible to refill the bottle, after the same has been emptied of its contents, any attempt to refill the bottle being defeated by the check valve arrangement, the check valves being inaccessible, except upon the complete destruction of the bottle and stopper.

With the above and other objects in view, the invention consists in the construction, combination and arrangement of parts, as will be hereinafter more fully described, illustrated in the accompanying drawings, and pointed out in the claims hereunto appended.

In the drawings: Figure 1 is a perspective view of a bottle, showing the improved stopper of this invention applied thereto. Fig. 2 is an enlarged perspective view of one section of the stopper, looking toward the channeled face thereof. Fig. 3 is a similar view of the other section of the bottle stopper.

The bottle stopper of this invention is primarily formed in two sections 1 and 2, and in the preferred embodiment of the invention the stopper, when complete, is substantially square in cross section, as indicated in Fig. 1. While this square form of stopper is especially useful in connection with very small bottles, the stopper may, of course, be made round in cross section, in the ordinary manner, when designed for use with bottles having larger necks. Such square stopper is shown mounted in the neck 3 of a bottle 4 in Fig. 1. The two sections of the stopper are divided on the angular line 5, thus providing each section of the stopper with a vertical meeting face 6, and an inclined or oblique meeting face 7.

In each of the meeting faces of the stopper sections, there is formed a channel, comprising an outer straight portion 8, and an inner straight portion 9. These straight portions 8 and 9 are formed partly in the

vertical face 6 and partly in the inclined face 7 of the stopper, and in the inclined face 7 said channels are expanded to form enlarged cavities 10 and 11 which, when the two sections of the stopper are finally brought together, constitute enlarged cavities, in which spherical check valves 12 and 13 are mounted. Within these enlarged cavities, I also provide oppositely arranged stop lugs 14 which serve to limit the movement of the balls 12, so as to permit the liquid to pass by the same in finding its exit from the bottle.

In the vertical face 6 of the stopper section, the channel is extended transversely at several points, as shown at 16, 17 and 18, and also vertically, as shown at 19, and near the junction of the portions 18 and 19 of the channel there is formed a safety chamber 20 adapted to receive any excess of liquid, after the bottle has been restored to its upright position. This prevents any overflow of liquid when the bottle is setting upright, and after a certain portion of the contents thereof has been poured therefrom.

The sections are further provided in their meeting faces with dowel holes 21 adapted to receive dowel pins, so as to properly position the two sections of the stopper with respect to each other, preparatory to cementing the sections together. The sections are further provided in their outer faces with key-ways 22 extending from the extreme upper edge of the stopper downward and having their lower ends enlarged, as shown at 23. The interior of the bottle neck is also provided with similar and complementary key-ways 22, so that after the stopper is inserted in the neck of the bottle and cemented therein, additional cement may be poured into the key-ways 22, thereby serving to permanently and reliably anchor the stopper in the neck of the bottle.

It will be understood that the two sections of the stopper are cemented together along their meeting faces, after the check valves have been inserted therein and the outer surface of the stopper as a whole is coated with cement preparatory to inserting the same into the neck of the bottle.

A cork or other form of stopper 24 may be inserted in the outer end of the serpentine canal to prevent spilling the contents of the bottle, when accidentally upset.

It will further be understood that when the two sections of the stopper are in final

complemental relation to each other, a tortuous, sinuous or serpentine canal is formed, leading from the inner to the outer end of the stopper, and that by reason of the inclination of the meeting faces of the stopper sections and the spherical check valves arranged in the cavities therein, it will be practically impossible to maintain one or both of the valves in such position as to render it possible to refill the bottle.

10 What is claimed is:

1. In combination with a bottle, a stopper closing the neck of said bottle, said stopper having opposing walls, said stopper formed adjacent said opposing walls with narrow channels opening out of said stopper in opposite directions, said stopper being formed with a zigzag intermediate elongated channel communicating with the inner ends of said first-named channel, means for holding said stopper against displacement from said bottle, the lowermost of said first-named channels being formed with a gradually enlarged part at its point of junction with said intermediate channel, a ball seated in said last-named channel at its point of juncture with its enlarged part, said intermediate channel being formed with a gradually enlarged part at its inner end sloping in a direction opposite to that of said first-named enlarged part, a second ball and a plurality of lugs arranged to seat said ball in the end of said second-named enlarged part, said

second-named ball arranged to close communication between the narrow ends of both 35 enlarged parts of said channels.

2. In combination with a bottle, a stopper composed of two sections, said sections composed of rectangular abutting parts and complementary beveled abutting parts, 40 means for holding said stopper against displacement from said bottle, said adjoined sections being formed with a continuous channel, said channel consisting of three branches, two of said branches extending 45 at opposite sides and opening out of said stopper at opposite ends and the third branch being an intermediate tortuous branch registering with the other branches, 50 said stopper sections in the plane of their beveled parts having the inner ends of the intercommunicating branches enlarged, said enlarged ends of said branches being formed each at an opposite end with a ball seat, a ball mounted in the seat formed by the lateral enlargement of said last-named branches, a plurality of lugs arranged to form a ball seat substantially in line with said other seat, and a ball mounted upon said lugs.

55 In testimony whereof I affix my signature 60 in presence of two witnesses.

WILLIAM H. MANNON.
